UNITED STATES PATENT OFFICE.

WILSON NOLES, OF INDIANAPOLIS, INDIANA.

FILTER.

Application filed November 17, 1922. Serial No. 601,525.

To all whom it may concern:

Be it known that I, WILSON NOLES, a citizen of the United States, residing at Indianapolis, in the county of Marion and State of Indiana, have invented new and useful Improvements in Filters, of which the following is a specification.

This invention relates to filtering devices and has for its object the provision of a 10 novel filter designed to be mounted within a water cooler or other receptacle and operating to continuously filter the water automatically so that all impurities and foreign matter will be removed and the water consequently made fit for drinking purposes.

An important and more specific object is the provision of a filtering device of this character which includes a receptacle within which the water, together with ice if preferred, is placed, the receptacle being provided in its bottom and also at spaced points along its sides with filtering elements.

An additional object is the provision of a device of this character which will be simple 25 and inexpensive in manufacture, highly efficient in use, durable in service and a general improvement in the art.

With the above and other objects and advantages in view the invention consists in 30 the details of construction to be hereinafter more fully described and claimed and illustrated in the accompanying drawings, in which:

Figure 1 is a vertical section through my 35 device mounted within a water cooler,

Figure 2 is a plan view, the cover of the cooler being removed,

Figure 3 is a horizontal section.

Referring more particularly to the drawings the letter A designates a water cooler of any ordinary or preferred type naturally provided with a cover and an outlet spigot. In carrying out my invention I provide an elongated cylindrical receptacle 10 40 constructed of galvanized iron, tin or other suitable material and suspended within the cooler A as for instance by having its bead 11 engaged upon lugs 12 which project from the inner periphery of the cooler. Any other 45 equivalent holding means may be provided if preferred.

In order to facilitate handling of this 50 receptacle, it is provided with a bail 13 which has its ends engaged within ears 14 on the inner periphery of the receptacle and this bail normally rests upon either one of a pair

of lugs 15 which are on the inside of the receptacle near the top thereof.

Extending inwardly from the inner periphery of the receptacle at points somewhat 60 below the top are lugs 16 which constitute a support for a somewhat tapered removable shelf 17 which is adapted to support ice and which is formed in the center of its bottom with a hole 18.

The lower end of the receptacle is open and formed with a retaining flange 19 upon which rests a disk 20 of natural stone or other material of a sufficiently porous nature to act as a filter. This disk is of course 70 securely cemented in place in addition to being held by the flange.

Located against the inner periphery of the receptacle at spaced points are metallic frames 21 each of which is rectangular in 75 shape and so constructed as to retain a block 22 of filtering material. The side edges of these frames lie against the inner periphery of the receptacle and the upper and lower edges are formed with curved flanges 23 80 which likewise bear conformingly against the receptacle. These frames are soldered in place and it will be apparent that there is provided a space 24 between each frame and the wall of the receptacle. The receptacle 85 is formed with holes 25 which communicate with the spaces 24.

In the use of the device it will be apparent that when the receptacle is suspended within a water cooler and water, together with 90 ice if desired, placed within the receptacle, it is apparent that the water will seep through the disk 20 at the bottom of the receptacle and drop into the cooler. At the same time the water will seep through the blocks 22 and accumulate within the spaces 24 from which it will flow through the holes 25. In this way it is apparent that the filtering action will be complete and automatic as well as sufficiently rapid 95 to filter a proper quantity of water in a reasonably short time. Whenever it is necessary the receptacle may be washed out thoroughly to remove any accumulation on the filtering disk or blocks so that the device 100 will be kept in a thoroughly sanitary condition.

While I have shown and described the preferred embodiment of the invention it is of course to be understood that I reserve 110 the right to make such changes in the form, construction and arrangement of parts as

will not depart from the spirit of the invention or the scope of the subjoined claims.

Having thus described my invention I claim:

- 5 1. A filtering device comprising an outer receptacle provided with a drain, an inner receptacle suspended within the outer receptacle in spaced relation to the walls thereof, rectangular frames secured upon the inner periphery of the inner member, flat slabs of porous material held within said frames, said frames fitting snugly against the inner wall of the inner receptacle whereby they together with the slabs 10 will define a plurality of compartments, the inner receptacle having its wall provided with openings communicating with said compartments.
- 15 2. A device of the character described comprising a double walled outer receptacle having a removable cover and provided at its bottom with a draw off cock, a plurality of brackets secured on the inner periphery of said outer receptacle near the top thereof 20 and arranged in equally spaced relation, an inner receptacle provided at its upper edge with a bead engaging upon said brackets whereby to effect suspension of the inner receptacle, a tray within the inner receptacle for holding a block of ice, and filtering means at the bottom and at the sides of the inner receptacle.
- 25 3. A filtering device comprising a receptacle formed in its side with spaced holes, and frames secured upon the inner periphery and defining spaces communicating with said holes, each frame carrying a block of filtering material, each frame being formed as a flat plate having its side edges lying against the inner wall of the receptacle and having its upper and lower edges formed with curved flanges conformingly engaging the receptacle, and each frame being furthermore formed with an opening surrounded by a retaining flange for the filtering material.

In testimony whereof I affix my signature.

WILSON NOLES.
